ELECTRIC TIMEPIECE

Stephen C. Cook, Brooklyn, N. Y., assignor to
Phinney-Walker Co., Inc., New York, N. Y.,
a corporation of New York

Application March 12, 1932, Serial No. 598,408

6 Claims. (Cl. 185—40)

This invention relates to electric timepieces and more particularly to the mechanism for effecting repeated partial rewinding of the driving spring.

5 Electric clocks have heretofore been provided with magnetically operated devices for maintaining the driving spring in the proper wound position. Suitable armatures mounted adjacent the magnets were provided with contact mechanism 10 to make and break the current automatically but it has been found that the apparatus was not sufficiently reliable and uniform to satisfy the requirements of clockwork or on the other hand, the apparatus was so large and difficult 15 to make as to be impractical and not at all suitable for an electric watch.

In the present invention I have provided a simplified contact mechanism which will operate continuously and regularly over a long period of 20 time and which is simple to manufacture and assemble and may be made small enough for application to a watch such as used on automobiles for example and which may be energized by low voltage current sources as are commonly 25 available on automobiles.

One of the principal objects of the invention therefore is to provide an improved contact mechanism for an electric watch having a periodically energized armature which causes a self-cleaning 30 effect on the contact surface due to the relative movement between the armature and the contact point, the contact being made at one point and rapidly broken at another point thereby preventing sparking and insuring instantaneous winding.

35 Another object of the invention is to provide a quick break mechanism for an electric watch contact circuit in which a separately powered lever acts to break the points at high speed to reduce arcing to a minimum.

40 Another object of this invention is to provide an electrical rewinding apparatus for a watch which is compact, inexpensive in construction and positive in operation and which will not interfere with any particular use of the watch 45 as for example in rear view mirror watch combinations for motor vehicles.

Another object of this invention is to provide an electric rewinding apparatus for a spring energized watch which may be confined within the 50 normal outline of the watch and with a relatively shallow depth and which will maintain the watch spring in the wound position with a minimum of power required and without objectionable effect on the continued running of the 55 watch.

Further objects and advantages of this invention will appear from the following description thereof taken in connection with the attached drawings which illustrate a preferred form of embodiment thereof and in which:

Figure 1 is an enlarged plan view taken from the rear of a watch. 60

Figure 2 is a side elevation of the watch shown in Figure 1 with parts broken away.

Figure 3 is a detail plan view of the contact mechanism showing the electric contacts in the closed position. 65

Figure 4 is a detail plan view similar to that shown in Figure 3 with the parts in advanced position to show further details of construction. 70

Figure 5 is a detail plan view of the contact breaking lever.

Figure 6 is a vertical section taken substantially through the center of the armature to show details of the contact mechanism. 75

Figure 7 is a plan view of the contact cam.

The electric watch shown in Figure 1 which is illustrative of one form of construction preferably comprises two separate parts, the clockwork mechanism A and the electric winding mechanism B. The clockwork mechanism A which may be a standard watch movement if desired, includes a frame 10 having the usual escapement 11 and power wheel 12 which drives a typical gear train to operate and turn the hands in the usual and well known manner. As illustrated, the clockwork is enlarged to show the details of the winding mechanism, it being understood that the apparatus may normally be of the size of a small watch or of any size as desired. The frame 10 80 is provided with suitable posts 13 to which a suitable cap or enclosure (not shown) may be secured. The clockwork mechanism A has the usual spiral coil spring removed and as will hereinafter be described, a substitute spring 14 is used to energize the power wheel 12 operating the escapement 11 and furnishing at all times the required power to operate the timepiece uniformly and continuously. 85

The motor winding apparatus B includes a pair of electrical solenoids 15 which are preferably mounted in alignment with an armature 16 between them. The solenoids 15 having arcuate poles 18 to increase the magnetic action on the armature 16, are carried by a suitable U shaped bracket 17 which is appropriately secured to the back of the watch casing A. Upon contact and energization of the solenoids 15 the armature 16 will be oscillated in the field of the 100

105

110

poles in the well known manner to rewind the spring 14 to its original tension.

The armature 16 carries a mutilated gear segment 24 having a spring arm 25 connected to the spring 14 acting as a direct source of power to rotate the gear portion 26 of the segment. The gear portion 26 is in geared relation with the spur gear 28 freely mounted on an independent shaft which contains the power wheel 12 which is adapted to rotate the gear train. The spur gear 28 is mounted in fixed relation to the operating lever 29 which in turn carries a pawl 30 operating on the ratchet gear 32, the ratchet gear being secured to the driving shaft 34 on which the work gear 12 is mounted.

As the armature rotates clockwise in the direction of the arrow shown in Figure 1, the mutilated gear rotates the spur gear and lever arm so that the work gear 12 operates in a counter-clockwise direction. Under normal circumstances the spring 14 energizes the mutilated gear in the clockwise direction to bring about the normal operating condition of the clock. If, however, the contacts close, energizing the solenoid, the armature will be rapidly rotated in a counter-clockwise direction as the armature is normally out of the pole pieces of the magnet as is well known and such movement will cause the pawl 30 to slip on the ratchet gear 32 without effecting the operation of the work gear 12. This movement will be counter to the work movement of the spring 14 and will take up the movement of the ratchet gear which will finally hold the spring in the extended position to further energize the clock work movement for an additional period.

The contact mechanism embraced in the electric circuit includes a spring arm 20 having a contact point 21 on the end thereof which cooperates with cam 19 having a contact face 22 which is carried by the armature. The contact surface 22 of the cam is more particularly shown in Figures 3, 4, and 7. This cam shaped contact surface 22 is in position to be contacted by the movable contact 21 but it also moves the contact point 21 under certain conditions. Primarily, however, the electric contact is made to close the circuit energizing the solenoids 15, which in turn operate the armature 16. Under proper winding conditions, the cam will assist to break the circuit without arcing.

As more particularly shown in Figures 3 to 7 inclusive, the contact surface 22 on the cam is of irregular shape and has points of different radius, the surface from 36 to 38 being of constant radius from the center 19b of the armature shaft, and the portion from 36 to 37 being flat and of constantly increasing radius. The cam surface from 37 to the end of the cam 39 is also flat, but at a less rapidly increasing radius from the center point.

As particularly shown in Figure 3, the contact point 21 is forced into contact with the cam surface 22 by the inherent resilience of the spring arm 20. At the particular point of contact the mutilated gear 26 is at substantially the furthest unwound position with respect to the spur gear 28 which condition exists when the spring is suitably unwound. The armature is connected to become energized however, and as such energization occurs the armature is moved to rewind the spring. The contact 21 is at a point corresponding to the point 38 on the cam surface 22 as is more particularly identified in Figure 7. In such condition the spring 14 which runs from the spring

arm 25 is still partially energized, sufficient to run the clock for a short period of time.

As soon as the armature is energized, however, the cam 19 rotates in a counter-clockwise direction as more particularly shown in Figure 4 until the point 37 is reached during which time the contact point 21 has exerted a wiping action along the constant radius surface between the points 36 and 38, and then has moved from the point 36 to the point 37 on an increased radius so that the spring arm 20 is flexed the difference between the respective radii. Such movement permits the catch lever 48 to operate, the lever 48 being carried on a suitable bracket 49 mounted on the watch frame 10.

The catch lever 48 is provided with a projecting catch 40 and the contact arm 20 is provided with a pin 42 which cooperates with the catch in such a manner that as the contact point 21 is forced away from the center 19b of the armature by the cam surface existing between the points 36 and 37 on the cam 19, the catch 40 will snap over the contact pin 42 and will hold the contact point 21 out of contact with the cam surface 22. The spring 44 cooperates with the catch lever 48 to exert sufficient force to snap the contact apart at the proper interval.

In the unwinding of the spring 14, the armature 16 rotates in a clockwise direction and the cam 19 moves to the left as more particularly shown in Figure 5. The cam has a lever releasing pin 46 which contacts with the catch lever 48 and after sufficient movement the contact pin 42 is released from the catch 40 as more particularly shown in Figure 3 to permit a snap contact between the contact point 21 and the cam surface 22. The catch 40 is provided with a sharp undercut surface to promote this effect.

As more particularly shown in Figure 1, the cam 19 is secured by suitable pins 19a to the armature 16, and the armature 16 is pinned to a central bushing 47, as shown in Fig. 6, which in turn is pinned to the mutilated gear segment 26 carrying the lever releasing pin 46 and carrying the spring cam 25. The contact 20 is appropriately placed with respect to the pin 42 to be held out of contact by the latch 40 when desired.

The magnets 15 are suitably wired and as shown a grounded return is preferably but not necessarily used. The wire 7 may thus be attached to 125 the metal support or frame A and the circuit will thus go through the cam 19, contact surface 22, contact point 21, contact supporting arm 20 and thence by the wires 8 to the respective magnets 15. The final wire 9 will then complete the 130 circuit.

In operation, the clock being in the wound position will run under force of the spring 14 until sufficient time elapses so that the armature reaches a substantially unwound position, 135 such as shown in Figure 3, at which time the latch controlling lever is released to bring about a contact between the contact point and the cam surface which simultaneously energizes the solenoids and begins a rotation of the armature. 140 This movement at first exerts a wiping action of the contact thus keeping the contacts clean and subsequently the cam surface forces the contact into such a position that it can be released by the wedging effect of the lever arm. This breaking 145 of the contact is brought about very rapidly due to the tension on the latch lever and the shape of the cam surface of the latch. The contact is thus made at one point on the cam surface, is broken at another point, and the contact surface 150

is continuously wiped and maintained in a suitable condition to afford a good electrical contact. The action is extremely rapid and takes place without affecting the normal clock movement.

5 The size of the spring 14 can be such that the contact is only made and broken once in a period of several minutes or it may be made so that it will only operate once in a period of several 10 hours. Considering the usual source of current on an automobile, however, which is usually a six volt battery, and considering the clock mechanism it is usually preferable to provide for re-energization of the spring once every two or three 15 minutes. The motion is noiseless, and is imperceptible and such arrangement requires but a small current to bring about effective results. Furthermore, the parts may be made sufficiently small so that an unusually accurate watch can be 20 made while it is obvious that the same structure could be used in an enlarged size of clock if desired. With such construction it is possible to use standard watch movements by merely removing the usual mainspring and simply attaching 25 the winding mechanism to the back of the clock. There are no parts to wear out or break and the operation of the watch is regular.

While I have shown a preferred form of embodiment of my device I am aware that other 30 modifications may be made therein and I therefore consider the present embodiments as illustrative rather than limitative of my invention and I therefore desire a broad interpretation of my invention within the scope and spirit of the disclosure herein and of the claims appended hereinafter.

I claim:

1. A winding control for timepieces which comprises a magnet, an armature operated thereby, 40 means to wind the mainspring by movement of said armature, a cam carried by said armature and forming one contact, a second contact, means to hold said second contact, out of position away from said cam in the normally wound position, 45 said cam releasing said holding means when said armature reaches a partially unwound position, means to close a contact between said contact and said cam, said means breaking said contact at a different point on the said cam when said 50 armature reaches a substantially wound position.

2. A winding control for an electrically wound spring driven timepiece having a periodically oscillated armature to maintain the spring tension within desired limits which comprises a cam shaped 55 contact surface carried by said armature, a second contact normally urged toward said cam contact, means on said cam to partially deflect said second contact, means to wedge said second contact away from said cam surface, and means carried by said cam to release said wedge.

3. A winding control for an electrically wound spring driven timepiece having an armature periodically oscillated to maintain the spring tension within desired limits, which comprises a cam 65 carried by said armature and having a contact surface thereon, said cam surface including a portion of constant radius and a portion of rapidly increasing radius, a spring contact normally urged towards said cam contact, the part of said cam 70 having a portion of rapidly increasing radius extending materially beyond other parts of said cam

whereby said spring contact is deflected, and a lever arm carrying a latch member, said latch member forcing said spring contact out of contact after said contact has been partially displaced, and means carried by said cam contact for releasing said lever when said spring is wound.

4. A winding control for an electrically wound spring driven timepiece having an armature periodically oscillated to maintain the spring tension within desired limits, which comprises a cam carried by said armature and having a contact surface thereon, a spring contact normally urged towards said cam contact, a part of said cam extending materially beyond other parts of said cam whereby said spring contact is deflected, and a lever arm carrying a catch member, said catch member forcing said spring contact out of contact after said contact has been partially displaced, means to bring about a snap contact of said spring contact arm on said cam, means to wipe said spring contact with respect to said cam surface to maintain an electrically clean contact, means to partially displace said spring contact by the surface of increasing radius, and means to force a wedge between said cam and said contact to break that circuit.

5. A winding control for an electrically wound spring driven timepiece having a periodically oscillated armature to maintain the spring tension within desired limits which comprises, a plurality of contacts, one of said contacts being cam shaped having a cam surface of increasing radius with respect to the other contact, the other contact having a surface acting as a cam follower, said armature wiping one of said contacts in closed 105 circuit relation on the other contact during substantially the entire period of movement of the armature, said wiping movement, moving one of said contacts transverse to the wiping movement, a pivoted lever, a latch element on said lever, said lever being juxtaposed with respect to the movable contact so that the latch element will engage the contact in its transverse movement to break the circuit, and means to trip the lever to 110 close the circuit at a different point.

6. An electric wound spring drive clock of the

class described including a main driving shaft, an oscillating armature and a ratchet drive between said armature and said drive shaft, a 125 spring normally rotating said armature to drive said shaft and an electric circuit to re-energize said spring and maintain its tension within desired limits, said electric circuit including a plurality of contacts, one of said contacts moving in an arc with the armature center as an approximate center and the other contact moving in a path toward and away from said center, one of said contacts having a cam face whereby movement of said contact in one path will cause a movement of the other contact in the other path, 130 a lever having a wedge latch thereon engageable with the contact movable in the path toward and away from the armature center when partially displaced by the other contact to break circuit, said lever being engaged by a projecting portion of the arcuately moving contact to release the other contact to release the circuit at a different point on the surface of the cam shaped contact.
